PLASTER BASE OR INSULATING MATERIAL

Edwin D. Coddington, Douglaston, N. Y., assignor
to Reynolds Corporation, New York, N. Y., a
corporation of Delaware

Application July 2, 1936, Serial No. 88,662

1 Claim. (Cl. 72—116)

This invention relates to plaster bases employed in building construction. More particularly the invention is directed to that type of plaster base comprising a sheet of flexible material bent back and forth to provide a series of folds or undulations and having straight, parallel stiffening wires or rods intersecting the hills and bridging the valleys of the undulations so as to form an anchorage for plastic material which is designed to be applied to one side of the sheet. Such a type of plaster base is described in my patent No. 1,750,877, dated March 18, 1930, upon which the present invention represents an improvement.

In the plaster base disclosed in said patent, a plurality of sheet metal or wooden stays are disposed within the bottoms of certain of the folds so as to preserve them against collapse and also to stiffen the sheet in a direction transverse to the reinforcing wires.

An important object of the invention is to provide a plaster base of the above character in which the stiffening stays are extended beyond one marginal edge of the sheet so as to overlie an adjacent sheet, and preferably being so arranged as to interfit with the stays of the latter sheet.

Other objects and advantages will become apparent from the following detailed description of a preferred embodiment of the invention, references being had to the accompanying drawing in which:

Figure 1 is a face view of a sheet of plaster base;

Figure 2 is a perspective view of a joint between two adjacent sheets of plaster base showing the manner in which the sheets are adapted to be assembled in a wall construction; and

Figure 3 is a cross-sectional view on the line 3—3 of Fig. 2 through the overlapped ends of a pair of adjoining sheets.

In Fig. 1 is disclosed a portion of a sheet of plaster base which is adapted to be nailed to the studs and joists of a building and to have a coating of plaster or stucco applied to its outer face in the construction of the walls, partitions and ceilings of the building. The base comprises a backing sheet of heavy building paper 1 bent back and forth so as to form a continuous series of regularly-spaced folds or undulations 2 extending in a horizontal direction between the edges of the sheet. Intersecting the hills and bridging the valleys of the undulations 2 at right angles thereto is a series of straight,

spaced, parallel metal wires or rods 3 which extend crosswise of the sheet.

These wires reinforce the sheet in a vertical direction and in order to stiffen the sheet in a horizontal direction a plurality of light, sheet metal stays 4 of generally U-shaped cross-section are disposed within alternate valleys upon the plaster-receiving side of the sheet and beneath the wires 3. These stiffening stays extend from a position flush with one margin 1a of the sheet to a position beyond its opposite margin 1b so as to overlap an adjoining sheet. The upstanding flanges of the U-shaped stays are welded or otherwise rigidly secured to the overlying wires 3. For imparting a better heat-insulating effect, the surfaces of the sheets 1 which face the dead air space within the hollow walls or partitions of a building (that is, the sides of the sheets opposite those which receive the plaster coating) are covered by a bright, heat-reflective material 5, such as aluminum foil.

The wires 3 terminate even with one edge 1c of the sheet and are extended a substantial distance beyond its opposite side 1d, as best indicated in Fig. 1. The purpose of this is to obtain sufficient overlap of the wires with respect to adjoining sheets of the plaster base to avoid cracking of the plaster adjacent the edges of these sheets.

As best indicated in Fig. 2, the association of the sheets of plaster base with the studding is such that two laterally adjacent sheets A and B are arranged in horizontally staggered relation with respect to a sheet C immediately above them so that the extended portions of the reinforcing wires of the lower sheets bridges the overlap with the upper sheet. These extended ends of the reinforcing wires are terminally directed downwardly toward the plane (i. e., the extended surface) of the sheet, as indicated in Fig. 2, so as to resiliently engage the adjacent sheet and to reduce the gap between the wires and the sheet. The vertical side edges of two adjoining sheets are disposed in abutting relation with the projecting portions of the V-shaped stays nesting within the bottoms of corresponding stays of the adjacent sheet. The sheets are affixed to the supporting studding S by nails or tacks 6 passing through the bottoms of the nested stays and backing sheet into the studs. Plaster is applied to the outer faces of the sheets in the customary manner.

As will be apparent, the projecting ends of the metal stays serve not only to facilitate aligning the sheets of plaster base horizontally in their

attachment to the studding, but such extensions also bridge the meeting edges of the sheets and serve to prevent the subsequent development of cracks in the plaster therealong. Additionally, 5 the double thickness of metal provided by the nesting of one end of a stay within another rigidly unites the sheets and avoids any tendency of the edge of one or both of the sheets to spread or buckle due to expansion or shrinkage, 10 or to lift away from or rock out of the plane of the contiguous sheet by reason of stresses imparted to the wall intermediate the studs, and thereby produce or promote cracking in this locality.

15 Manifestly the invention may be embodied in other forms than that described above, which latter is to be considered simply as illustrative.

I claim:

A reinforced plaster-supporting fabric comprising a sheet of flexible fibrous material bent back and forth to provide a series of regularly-spaced undulations, a plurality of reinforcing wires passing transversely through the undulations, said wires terminating even with one of the edges of the sheet and being extended beyond the opposite edge of the sheet and the ends of said wires being bent toward the surface of the sheet, and a plurality of sheet metal stays 10 of trough-shaped cross-section seated within the bottom of certain of the undulations and having their side walls rigidly affixed to the reinforcing wires, said stays terminating even with one edge of the sheet and projecting beyond the opposite 15 edge of the sheet.

EDWIN D. CODDINGTON.
